UNITED STATES PATENT OFFICE.

JOSHUA W. JONES, OF HARRISBURG, AND JOSEPH R. JONES, OF PHILADELPHIA, PENNSYLVANIA, ASSIGNORS OF ONE-THIRD TO THOMAS A. JONES, OF PHILADELPHIA, PENNSYLVANIA.

COMPENSATING DEVICE FOR RAILROAD SIGNALS, SWITCHES, &c.

SPECIFICATION forming part of Letters Patent No. 578,293, dated March 2, 1897.

Application filed September 25, 1896. Serial No. 606,951. (No model.)

To all whom it may concern:

Be it known that we, JOSHUA W. JONES, residing at Harrisburg, in the county of Dauphin, and JOSEPH R. JONES, residing in the city and county of Philadelphia, State of Pennsylvania, citizens of the United States, have invented a new and useful Improvement in Compensating Devices for Railroad Signals, Switches, &c., which improvement is fully set forth in the following specification and accompanying drawings.

Our invention has relation to a compensating device for railroad signals, switches, &c.; and it consists in the employment of a lever suitably fulcrumed and having connections therefrom to a fixed point and to a dog or pawl, which latter is actuated, as hereinafter described, when the proper arm of the operating-lever is in inferior position.

It further consists of novel details of construction, all as will be hereinafter fully set forth, and specifically pointed out in the claims.

Figure 1 represents a side elevation of a compensating device for railroad-signals embodying our invention. Fig. 2 represents an end elevation of a portion of a yoke and spring-actuated pawl employed. Fig. 3 represents a plan view of the offset ceiling-bar seen in Fig. 1. Fig. 4 represents a side elevation of another embodiment of the principle of our invention as applied to a corrugated disk and a corrugated pawl eccentrically mounted adjacent thereto. Fig. 5 represents a perspective view of a removable weight employed; and Fig. 6 represents a sectional view, on line *xx*, of the weight, showing the manner of supporting the same.

Similar letters of reference indicate corresponding parts in the several figures.

Referring to the drawings, A designates an operating-lever which is fulcrumed at a suitable point B and is provided with the laterally-extending arms C and D, upon which are mounted the yokes E and F, and since the mechanism carried by each yoke is substantially the same a description of one will suffice for both, reference being had to the right-hand yoke E.

G designates a lever which is fulcrumed in the present instance at H to said yoke E, and has attached to one end thereof one extremity of the link J, the other extremity thereof being pivoted to the weighted end K of the pawl L, which is movably mounted in said yoke E and has a nose M, which is adapted to engage the teeth of the ratchet-wheel N, which is preferably provided with a sprocket-hub. (Not shown.)

P designates a spring which is mounted upon the hub of the pawl L, and has its extremities Q and R deflected, so as to engage suitable portions of the yoke E and said pawl L, respectively, as will be understood from Fig. 2, so that the tendency will always be for the nose M of the pawl to engage the ratchet-wheel N when the lever G is released or is in the position seen at the left of Fig. 1.

S designates a rod extending through a suitable portion of the lever G and having its upper extremity attached to the adjustable eyebolt Y, which passes through the bar T and is held in position by means of the lock-nuts Z, said lever being actuated by the contact of the nut S⁵ therewith, said nut engaging said lever at the proper intervals, as will be explained.

The bar T consists of the portions U and V, which are attached to the floor-beams in any suitable manner, said bar being provided with an offset W in order to permit the proper extent of movement to be imparted to the lever A, and having a plurality of openings therein, through which the eyebolts Y are adapted to be passed, whereby the position of the rod or connection S can be shifted according to the requirements.

A' designates a chain or similar connection which passes over the hub of the ratchet-wheel N, said connection having an extension B', which is adapted to lead to a signal, switch, or other similar device. The connection A', after passing over the hub of the wheel N, passes thence under the pulley C', and is attached to a suitable portion D' of the traveling pulley E', which is supported upon a chain F', which latter has one extremity attached to the eyebolt or similar

device G' which engages the beam G² while the left-hand portion of said chain F' passes over the hub of the ratchet-wheel J', which is journaled in the yoke F, said wheel J' and its adjuncts being in all respects substantially the same as the wheel N and its adjuncts already described, it being understood that suitable connections K' extend from the chain F' to a proper portion of the signal or switch. (Not shown.)

L' designates a plurality of chains which have one of their ends suitably secured to the beam G² or other point, while their other ends are attached to a link which is attached to the pin which passes through the pulley C'.

M' designates a strap or yoke which depends from the pulley C' and carries the weights N' therein, the same being increased or diminished, as desired, by the addition of other weights P', said latter weights being connected to each other by means of the supporting devices Q'.

In Fig. 4 we have shown another embodiment of the principle of our invention, E designating the yoke, as before, in which is journaled the corrugated disk R', which is adapted to be locked and engaged by the corrugated pawl S', which is eccentrically mounted, said pawl having a body portion T', to which the counterbalance U' is attached, to which one end of a suitable link-and-lever connection may be secured, while the other end thereof is attached to any desired fixed point, said pawl T' being also provided, if desired, with a spring P' of substantially the same construction as that seen in Figs. 1 and 2.

The operation is as follows: If we suppose the lever A to be moved from the right to the left, the arm C will be raised and the arm D lowered. As the arm C rises the connection S, which in the present instance is a rod, will pass through the opening in the lever G as the latter rises and the spring P of the counterbalance K will cause the nose M of the pawl to interlock with an adjacent tooth of the ratchet-wheel N. The latter, being now prevented from rotation and the chain A' being prevented from movement relative thereto and being lifted upwardly with the yoke, wheel N, and arm C, will exert a pull on the connection B' in the direction of the arrow, thereby imparting the proper movement to the signal arm, switch, &c. The arm D has in the meanwhile been descending, and as soon as it has reached a certain predetermined inferior position the nut S³ on the rod S² will disengage the lever S⁴ which corresponds to the lever G and will unlock the pawl automatically from the teeth of the disk J', thereby allowing said disk to freely revolve, and any slack on the connections A' and F' will be immediately taken up by means of the traveling weights N' or P', it being understood that the arm C is now in elevated position, while the arm D is in depressed position.

The operation of the mechanism seen in Fig. 4, it is thought, will be clearly understood from the foregoing, it being only necessary to substitute the corrugated disk R and the corrugated eccentric S' for the ratchet-wheel N and the pawl L, having the nose M, as already described.

In the preferred embodiment of our invention we employ weights substantially as seen in Figs. 5 and 6, N' designating the weight, having the end portions B² with an offset neck or body portion C², the same having the face D² raised above the surfaces of the end portions B², the sides D³ of said neck being rounded, and each weight having also holes E² therethrough for the insertion of suitable attaching devices, as seen in Fig. 1.

The manner of inserting the weights in position will be apparent from Fig. 6, in which one weight is shown in position and the other in the act of being inserted in place, the latter weight having its thinner portion introduced, first, into the strap or yoke M' and being afterward turned into position, the weights, when finally superposed upon each other, being interlocked, as is evident, whereby there is no liability of accidental displacement or dislodgment of the same.

Having thus described our invention, what we claim as new, and desire to secure by Letters Patent, is—

1. In a compensating device, a lever having oppositely-extending arms with yokes thereon, ratchet-wheels journaled in said yokes and having sprocket-hubs, a traveling pulley supported on a chain having one end secured to a fixed support, and its other end passing over one of said sprocket-hubs and connected with a signal or other device, a weighted pulley supported on a chain having one end secured to said traveling pulley and its other end passed over the other sprocket-hub and connected with said device, and mechanisms connected with said yokes for automatically locking and unlocking said ratchet wheel and hubs.

2. In a compensating device, a lever having arms with yokes mounted thereon, each of said yokes having a ratchet-wheel with a sprocket-hub and a spring-controlled pawl engaging said ratchet-wheel, mechanism for automatically releasing said pawl on alternate movements of said arms, chains connected with fixed support and passing over said hubs respectively, a traveling pulley on one of said chains, and a weight-pulley on the other chain, and chains secured to said fixed support and to links on the axle of said weight-pulley.

3. In a compensating device, a lever, a yoke on an arm thereof, a ratchet-wheel journaled in said yoke, a spring-controlled pawl pivotally mounted and adapted to engage said wheel, a lever suitably fulcrumed and having a link common to itself and to said dog, and a depending rod passing through an opening in said lever and provided with a nut thereon

for actuating said lever at proper intervals, in combination with a weighted chain passing over said wheel and adapted to lead to a signal-arm.

5. In a compensating device, an operating-lever suitably fulcrumed, arms extending laterally therefrom, yokes mounted on said arms, ratchet-wheels journaled in said yokes, weighted chains passing around hubs on said ratchet-wheels and having connections leading to a signal-arm, switch, &c., pawls pivotally supported and adapted to engage said wheels, levers suitably fulcrumed, links common to said levers and dogs, and means for locking and unlocking the latter, whereby one of said dogs and its wheel are enabled to be in engagement when in elevated position, and are disengaged when in depressed position.

6. In a compensating device for a signal-arm, a yoke suitably supported, a ratchet-wheel journaled therein, a pawl mounted on said yoke, a spring adapted to normally cause the nose of said pawl to engage said wheel, a lever suitably fulcrumed, a link common to said lever and pawl, a connection from said lever to a fixed point, a weighted chain passing over a suitable portion of said wheel, and connections therefrom to a signal, switch &c.

7. In a compensating device, an operating-lever having laterally-extending arms thereon, yokes mounted on said arms having ratchet-wheels journaled therein, pawls adapted to engage said wheels, a link-and-lever connection common to said dogs and to said yoke, a rod having one end attached to a fixed point and its other end passing freely through said lever, a nut on said rod underneath said lever, a weighted chain passing over said ratchet-wheels, and connections from said chain adapted to lead to a signal-arm, switch, &c.

8. In a compensating device, a yoke, a ratchet-wheel journaled therein, a pawl pivotally mounted adjacent said wheel, a counterbalance attached to said pawl, a spring bearing on the latter, a link-and-lever connection common to said pawl and yoke, a connection from said lever to a fixed point, and connections passing over said wheel and adapted to lead to a signal-arm, switch, &c.

9. In a compensating device, a plurality of ratchet-wheels suitably supported, pawls adapted to unlock said wheels when in depressed position, a link-and-lever connection common to said dogs and to their support, and a connection from said lever to a fixed point, in combination with chains or other connections passing over said wheels, one of said connections being secured to a fixed point and carrying a traveling pulley, and the other of said connections being secured to said pulley and carrying a traveling weight.

10. In a compensating device, laterally-extending arms, ratchet-wheels journaled upon each of said arms, pawls for locking said wheels, and a link-and-lever connection for operating said pawls, in combination with

chains adapted to lead to a signal, switch, &c., passing over said wheels, one of said chains being attached to a fixed point, and carrying a traveling pulley, while the other of said chains is attached to said pulley and carries a traveling weight.

11. In a compensating device, laterally-extending arms, ratchet-wheels suitably journaled thereupon, pawls adapted to engage and lock and unlock said wheels, a link-and-lever connection for operating each of said pawls, a connection leading from each of said levers to the offset ceiling-bar P, means for supporting said bar, weighted chains passing over suitable portions of said wheels, and connections from the latter adapted to lead to a signal, switch, &c.

12. In a compensating device, laterally-extending arms, ratchet-wheels suitably journaled thereupon, pawls adapted to automatically engage and lock and unlock said wheels, means for releasing the latter, chains passing over suitable portions of said wheels, connections from said wheels adapted to lead to a signal-arm, switch, &c., a pulley supported upon one of said chains, a strap or yoke attached to said pulley and depending therefrom, a plurality of weights carried by said strap, and means for adding or subtracting weights to said strap.

13. The herein-described weight consisting of the end portions B², and the connecting-neck C² having its upper and lower faces out of alinement with the upper and lower faces of said end portions.

14. The herein-described weight consisting of the end portions B², and the connecting-neck C² having its upper and lower faces out of alinement with the upper and lower faces of said end portions, said neck being also provided with curved sides.

15. In a compensating device, a yoke or strap consisting of two upright members joined together at their extremities, in combination with a weight adapted to be inserted within said strap, said weight being provided with end portions, and a connecting-neck having its upper and lower faces out of alinement with the upper and lower faces of said end portions.

16. In a compensating lever, an operating-lever having laterally-projecting arms, compensating devices mounted on each arm, an offset ceiling-bar suitably supported, and a link-and-lever connection to each compensating device, in combination with connections leading from said last-mentioned levers to an eyebolt supported in said ceiling-bar, the position of said eyebolts being adjustable according to requirements.

17. In a compensating device, an operating-lever, a laterally-extending arm, a ratchet-wheel mounted thereon, a pawl engaging said wheel, a yoke in which said pawl and wheel are supported, a link-and-lever connection for said pawl, and a spring, said spring being

mounted on a suitable portion of said pawl and having its ends deflected, one of said ends engaging said yoke, and the other end engaging said pawl.

5 17. In a compensating device, an operating-lever, a laterally-extending arm, a yoke mounted on the latter, a ratchet-and-pawl device supported by said yoke, means for unlocking said pawl at the proper intervals and 10 restoring a spring, said spring being mounted on a suitable portion of said pawl and having its ends deflected, one of said ends engaging

said yoke, and the other end engaging said pawl.
